Design No. 18,008 dated January 10, 1968.

1905

1905

UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S COAT.

SPECIFICATION forming part of Design No. 18,008, dated January 10, 1888.

Application filed December 8, 1887. Serial No. 257,466. Term of patent 3½ years.

To all whom it may concern:

Be it known that I, HENRIETTA F. DUKE, of the city, county, and State of New York, have invented and produced a new and original Design for a Pattern of a Lady's Coat; and I do hereby declare that the engraved prints accompanying this specification convey to any one accustomed to using paper patterns a clear understanding of how a garment made up by

10 the pattern will appear.

The design shows long single-breasted fronts that display a closing at the center, a close-fitting back that shapes a point at the center of its lower edge, a full-gathered back skirt 15 depending from the lower edge of the back, and cape sections which extend across to the closing from the side back seans, present the

dolman arch over the shoulders and display revers turning over from the front edges, the revers tapering toward the neck, the lower 20 outline of each cape-section describing a deep point at the front edge, a high arch across, and a shorter point at the back edge, a rolling collar, and coat-sleeves.

What I claim as my invention, and desire to 25 secure by Letters Patent, is—

The design for a lady's coat, as shown in the engraved prints accompanying this specification.

HENRIETTA F. DUKE.
